US00D973104S

(12) **United States Design Patent** (10) Patent No.: **US D973,104 S**
(45) Date of Patent: **** Dec. 20, 2022**

(54) **CONSOLE FOR PNEUMATIC COMPRESSION DEVICE**

(71) Applicant: **Therabody, Inc.**, Los Angeles, CA (US)

(72) Inventors: **Jaime Sanchez Solana**, Los Angeles, CA (US); **Brian Carberry**, Beverly Hills, CA (US); **Brian Zeng**, Dongguan (CN); **Washington Alexander Silva Garces**, Los Angeles, CA (US); **William Webb**, San Francisco, CA (US)

(73) Assignee: **Therabody, Inc.**, Los Angeles, CA (US)

(**) Term: **15 Years**

(21) Appl. No.: **29/825,453**

(22) Filed: **Feb. 1, 2022**

(51) LOC (13) Cl. **15-02**

(52) U.S. Cl.

USPC **D15/7; D24/200**

CLAIM

The ornamental design for a console for pneumatic compression device, as shown and described.

DESCRIPTION

FIG. 1 is a perspective view of a console for pneumatic compression device, showing our new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof; and,

FIG. 7 is a bottom plan view thereof.

The broken lines in the figures show portions of the console for pneumatic compression device that form no part of the claimed design.

1 Claim, 7 Drawing Sheets
